UNITED STATES PATENT OFFICE

STEWART L. CAMPBELL, OF BERKELEY, CALIFORNIA, ASSIGNOR TO JOHN GRANT, OF LOS ANGELES, CALIFORNIA

SLIP ELEVATOR

Application filed July 2, 1929. Serial No. 375,464.

This invention has reference to pipe supporting apparatus, pipe elevators, spiders and the like, of the character used in well drilling operations, and has to do particularly with apparatus of this nature embodying wedge slips for gripping and supporting the pipe. It may be stated that certain features of the invention are broadly applicable to pipe supporting apparatus in general, but for the purpose of giving a specific and typical example of its adaptation, I shall herein describe the invention as embodied in a gate-type elevator. And in connection with its application to this particular type of elevator, it may be noted that the invention enables the use of the usual pipe surrounding wedge slips in a gated elevator without interfering with the normal gate operation of this type of apparatus.

Although in the present form of the invention, I have illustrated an elevator body comprising a pair of pipe encircling parts and within which is the pipe receiving opening containing wedge slips, it will be understood that the invention in certain of its aspects is not limited to the use of a sectional form of body, and that it broadly contemplates the use of either a sectional—or single—part body for a pipe elevator or a stationary pipe support, for instance a spider. In other respects, however, my invention has certain particularly advantageous features in association with sectional or gated type bodies, and therefore it is hereinafter described in a form comprising that type of body.

It is one purpose of the invention to provide preferably a gated slip-type elevator having the inherent advantageous features of a gated body and also those characteristic of the use of wedge slips for gripping and supporting the pipe. In another copending application on gated slip elevator, Ser. No. 324,006, filed Dec. 5, 1928, I describe a gate-type elevator in which the body portion carries vertically movable wedge slips, and the gate portion, in addition to swinging horizontally, is adapted to move downward and inward toward the pipe and into gripping engagement therewith together with the slips,

stationary dies being carried in the gate for this purpose.

In the present type of elevator, the gate preferably has horizontal swinging movement only and vertically movable wedge slips are carried both on the body and gate portions, all the slips being movable together when the gate is in closed position. To operate the slips, I provide a segmental and rotatable cam ring carried within the pipe receiving opening between the body and gate, the cam ring comprising two parts, one each for the body and gate. Wedge slips are supported on the ring assembly and caused, by cam action, to move vertically when the ring is rotated. The cam ring sections being in end to end engagement, rotation of one section serves to rotate the other, and when the slips are in work releasing positions, the cam ring is in a position such that it "breaks" substantially in the plane of engagement between the body and gate, and the latter therefore may swing freely without binding caused by an overlapping cam ring section. Such binding may be utilized, however, to prevent opening of the gate when the slips are in their lower or work engaging positions, although additional means is provided for insuring locking of the gate in closed position when the wedge slips are lowered.

These and additional features of the invention will be discussed more fully and to best advantage in the following detailed description, reference being had therein to the accompanying drawings, in which:

Fig. 1 is a front elevation of the elevator;
Fig. 2 is a plan view of Fig. 1;

Fig. 3 is a horizontal section on line 3—3 of Fig. 1 and the gate being shown swung in open position;

Fig. 4 illustrates a vertical section on line 4—4 of Fig. 3, the wedge slips being shown in dotted lines to illustrate more clearly their positions relative to the body section of the cam ring;

Fig. 5 is a section on line 5—5 of Fig. 2;

Fig. 6 is an enlarged fragmentary section on line 6—6 of Fig. 2, the wedge slips being shown in raised or work releasing positions;

Fig. 7 is a view similar to Fig. 6 but show-

ing the slips in their lowermost or work engaging positions;

Fig. 8 is a diagrammatic developed illustration of the cam ring as it would appear if spread flat;

Fig. 9 is a fragmentary section on line 9—9 of Fig. 2;

Fig. 10 is a section on line 10—10 of Fig. 7; and

Fig. 11 is a section on line 11—11 of Fig. 2.

Referring to the drawings, the elevator comprises the two pipe encircling parts 10 and 11, the former of which may be termed the body portion, and part 11 the gate. Lugs 12 are provided on opposite sides of the body and have bearing on the usual elevator supporting bails 13. The gate 11 is hinged at 14 on one end of the body, and is adapted to swing horizontally from the closed position of Fig. 2 to the open position shown in Fig. 3. The gate is cut away to form the hinge lugs 11a, 11b above and below the body lug 10a, hinge pin 15 extending vertically through these lugs and terminating in the reinforcing pieces or links 16 and 16a. Reinforcing pin 17 extends through the body 10 and also terminates in the upper and lower reinforcing elements 16, 16a. If it is desired, the body 10 may be cast as a single part including portions 16, 16a, and pin 17 eliminated by casting the body solid. However, it may be preferred that these parts be provided separately and assembled as described, in order to give maximum strength to the hinge joint 35 and to provide reinforcement against stresses imposed on the elevator under load tending to spread apart the gate and body portions. Thus the body 10 may be formed of material particularly suited to its casting or machining, and the pins 15, 17 and the interconnecting links 16, 16a formed of comparatively stronger material, the effect being that the body and gate parts are held together at their hinge end by a yoke of great strength, 45 and the parts at the same time being hingedly connected.

The free end of the gate is shaped to provide the vertically spaced lugs 18, 18a, having curved cam faces 19. In the closed position 50 of the gate, the inner body lug 10c projects between the vertically spaced gate lugs. A yoke 20 is mounted on vertical pin 21 carried in the body, the yoke being adapted to swing horizontally about pin 21 and to extend around the gate lugs 18, 18a, as illustrated in Figs. 2 and 5, to lock the gate in closed position. It may be mentioned that preferably the yoke and pin 21 are formed of material having comparatively great 55 strength in order to resist the forces tending to swing the gate when the elevator is under load.

The yoke is yieldably urged into closed position by suitable means, for instance 60 springs 23, 24 confined on the upper and

lower back portions of the body between links 16, 16a and lugs 25, 25a formed on the yoke. Assuming the gate to be swung from open to closed position, the outer curved faces 19 of the gate lugs engage the yoke, swinging it outwardly against the resistance of springs 23, 24, until the gate lugs pass within the yoke, whereupon the latter is returned to its normal gate closing position. Thus it will be noted that the yoke operates essentially as a latch for confining the gate.

A sleeve-like hub 27 is mounted on the gate and is capable of limited rotational movement about pin 28 retained at its ends in the gate web portions 29, the hub having a pair of integral lugs 30 on its inner side which, in the dotted line position of Fig. 2, engage the gate proper to limit the turning of the hub about pin 28. The hub also has an integral pair of arms 32, 32a which normally seat within recesses 34 in the outer end of the gate to permit movement of the yoke 20 into substantially flush position thereagainst. The hub is rotated by means of a handle, not shown, which may be inserted in the hub socket 37. With the parts in the position shown in Fig. 2, hub 27 may be turned in the direction of arrow A to throw arms 32, 32a out into engagement with the yoke 20, whereupon the latter is swung outwardly to the dotted line position 20a. The yoke thus is swung out to release the gate lugs 18, 18a and to permit the gate to be swung open. Springs 23, 24, of course serve to return the actuating arms 32 as well as the yoke to their normal positions after the gate and hub are released. It may be noted at this point that when the pipe is being supported by the elevator, or when the elevator parts are in pipe supporting positions, the gate is prevented from being opened, and as will later be seen, this provision is made by locking the hub 27 against rotation when the wedge slips are in work engaging position, thereby preventing the yoke 20 from being swung to release the gate, hub 27 however being released for yoke releasing rotation when the wedge slips are returned to their work releasing positions.

A vertical pipe receiving opening 39 is formed in the pipe surrounding parts 10, 11, the sides 39a of the opening converging downwardly as shown in Fig. 4. Vertical channels 40, four being shown as typical, are cut in the walls of opening 39 in the body and gate portions, the channels preferably extending the full length of the opening. A plurality of vertically movable wedge slips 42, one for each channel 40, is mounted on both the body and gate, the outer faces 42a of the slips being curved to bear against the curved tapered wall 39a of the opening, and the inner faces of the slips being provided with pipe gripping teeth 42b. The slips have longitudinal rib portions 43 formed on their outer faces riding in the body and gate chan-

nels 40. Transverse or circumferential openings 44 are formed through the rib portions 43, and a roller 45 is mounted within each of the openings at a suitable intermediate point. To facilitate construction of the slip in this manner, I may provide the opening 44 by forming a longitudinal recess 45 in the rib and mount the roller 45 on a pin 47 bearing at its ends in the body of the slip 5 and in a plate 48 secured to the back of the slip at the ends of the opening. The rib portions of the slips preferably, though not necessarily, have a slight amount of clearance from the bottom of the longitudinal channels 40, backing for the slips being provided at their outer faces 42a in engagement with the walls of opening 39. The slips are prevented from being moved upwardly and out of the elevator by means of stops 49 10 threaded in the body at the upper ends of the channels 40.

Referring particularly to Figs. 2 and 10, it will be noted that the body has tapering cylindric-surface ways 70 corresponding in shape 15 to the cylindric outer faces 42a of the slip. Thus both the slip faces 42a and ways 70 are of cylindrical shape but are arranged in tapering formation. In Fig. 10, R represents the radius of the bottom of the tapered pipe 20 receiving opening 39, S the radius of curvature of the back face 42a of the slips, and T the radius of curvature of the top outer edge of the slip, the dotted line 71 diagrammatically indicating the upper end of the 25 slip relative to its lower portion shown in section. Radii R, S and T being substantially equal, it will be noted that ways 70 diminish downwardly in depth and also that at the bottom of opening 39, the curved surfaces of the ways disappear into the surface 30 of the pipe receiving opening. In other words, the radius S of the outer face of the slips and radius R, are preferably the same. Thus to enable the slips to have backing engagement with the walls of the pipe receiving 35 opening 39 over the entire area of faces 42a, the cylindric ways 70 are shaped in conformity with the slip faces 42a and are deepened upwardly in accordance with the downward taper of opening 39.

Both the gate and body portions are annularly recessed within the central opening 39 to form the annular channel 50, the back surface of the channel preferably converging 40 downwardly at a slope corresponding to the taper of the walls 39a of opening 39, and the channel sections in body and gate registering when the gate is in closed position. A rotatable and segmental slip actuating 45 cam ring, generally indicated at 51, is carried within channel 50, the cam ring comprising two parts 51a and 51b, for the body and gate portions 10 and 11, respectively. With the elevator closed, the ends of the cam ring sections 50 abut and thus rotational movement im-

parted to one of the sections serves to rotate the entire cam ring. A plurality of inclined slots 53, one for each wedge slip, is formed in the cam ring at equally spaced intervals around the ring, the vertical depth of the slots governing the range of vertical movement of the wedge slips. As indicated particularly in Figures 6 and 8, the sections of the cam ring are shaped to provide, in effect, when the sections are in engagement, a continuous cam ring having continuous slots 53 at spaced intervals therearound. The circumferential extent of the slots 53 is such that alternate slots "overlap" both cam ring sections, that is for example (see Fig. 8) at the abutting ends of the ring sections the upper portion 53c of the "overlapping" slot is defined by the vertically spaced inclined edges a, b, of both ring sections 51a, 51b, the lower portion 53d of the slot being formed exclusively in the ring section 51a. The cam rim sections extend laterally through the transverse openings 44 in the slips, the cam ring supporting the slips by virtue of the engagement of rollers 45 within slots 53. It will be noted that at their upper ends, the slots extend horizontally, as at 53a, for a short distance sufficient to enable the rollers 45 to perch in the horizontal slot portions, and thereby to retain the slips in their raised or work releasing position.

The cam ring is rotated by means of a handle 55 inserted within a tubular extension or socket 56 mounted on the ring section 51b, the extension 56 projecting outward through a horizontally extending opening 58 in the front of the gate. Thus, when the gate is closed, the cam ring may be rotated within the limits permitted by the gate opening 58 by means of handle 55. Assuming the wedge slips to be in raised or work-releasing position, and the cam ring to be in the position indicated in Figures 1 and 6, by moving handle 55 to the left, the cam ring is caused to turn to the position of Figure 7, and the slips to become lowered due to the rollers 45 riding down the inclined slot faces 53b as the ring is rotated. Of course, the diameter of the pipe 60 to which the elevator is applied may determine the lower limiting positions of the slips, that is, the slips may come into wedging engagement with the pipe at any point intermediate their uppermost and lowermost positions. Thus when the elevator parts are in pipe supporting positions, the rollers 45 may rest at some intermediate point on the inclined faces 53b. It will be noted that since the slips are confined against lateral movement, and with the diameter of the rollers 45 substantially the width of slots 53, vertical movement of the slips in their intermediate vertical positions within the slots is prevented by the engagement of rollers with the upper and lower defining sides of the slots. To raise the wedge slips and to return them

to their uppermost positions indicated in Figures 4 and 6, the cam ring is rotated in a reverse direction, the inclined faces 53b formed by the slots engaging the rollers, and by cam action causing the slips to be raised, and retained in raised position by virtue of the rollers becoming perched in the horizontal slot portions 53 a.

As stated hereinabove when the wedge slips are in work-engaging position, means is provided for locking the sleeve 27 against rotation to prevent swinging of the yoke 20 and thereby enabling the gate to open. Such locking means typically may comprise a horizontal movable door 61 mounted on the gate 11 and adapted to be actuated by the cam ring socket extensions 56. The door 61 has a central opening 63 having a horizontal extent somewhat less than that of the gate opening 58, and a pair of horizontal slots 64 above and below opening 63, screws 65 extending through slots 64 to mount the door on the gate and to guide the door in its horizontal movement when actuated by extension 56. As will be noted in Figure 3, the yoke actuating hub 20 has a flat recess 66 in its inner side to take the door 61 when the latter is moved between the hub and the gate, and as the slips are released from their upper position to lower work-engaging position. Again assuming the parts to be in the positions of Figures 1 and 4, upon turning handle 55 to the left to release the slips, cam ring extension 56 is brought into engagement with the door 61 at the end of opening 63, causing the door to be moved into place within the hub recess 66, as indicated in the dotted line position 61a in Figure 2. Thus by virtue of the positioning of the door within the hub recess 66, the hub is prevented from being turned, and yoke 20 therefore prevented from opening to release the gate. The hub, of course, is released upon returning the slips to raised position, in which operation the door is moved into its corresponding position indicated in Figure 1.

It will be noted that although I have provided for positively locking the gate and body portions of the elevator in closed position when the wedge slips are lowered, the cam ring itself may serve as a means for preventing opening of the gate by virtue of the overlapping of the ring segments in both the body and gate channel portions, as indicated particularly in Figure 7. Thus in this position of the parts the ring segments may so interlock the gate and body as to prevent opening of the gate. Upon returning the slips to raised positions, however, the corresponding positions of the cam ring segments are such that they are contained substantially entirely, except for the slight overlap necessary to form the slots 53, contained within the gate and body portions, thereby

enabling the gate to swing open and the cam ring to "break" without binding.

It will be understood the drawings and description are to be considered merely as illustrative of and not restrictive on the broader claims appended hereto, for various changes in design, structure and arrangement may be made without departing from the spirit and scope of said claims.

I claim:

1. An elevator of the character described, comprising two body parts which together encircle the pipe, said body parts having a pipe receiving opening, a pair of vertically movable wedge slips, one for each body part and arranged within said opening, and manually operable means for controllably moving the slips vertically.

2. An elevator of the character described, comprising two body parts which together encircle the pipe, said body parts having a pipe receiving opening, a vertically movable wedge slip therein, and cam means for moving the slip vertically.

3. An elevator of the character described, comprising two body parts which together encircle the pipe, said body parts having a pipe receiving opening, a vertically movable wedge slip therein, and a segmental slip actuating cam ring mounted within said opening and engaging said slip, the cam ring being rotatable to move the slip vertically.

4. An elevator of the character described, comprising two body parts which together encircle the pipe, said body parts having a pipe receiving opening, a pair of vertically movable wedge slips therein, one for each body part, a segmental slip actuating cam ring mounted within said opening and supporting said slips, the cam ring comprising two parts, one for each body part, and the ring being rotatable to move the slips vertically.

5. An elevator of the character described, comprising two body parts which together encircle the pipe, said body parts having a pipe receiving opening, a plurality of vertically movable slips therein, a segmental slip actuating cam ring mounted within said opening and comprising two parts, one for each body part, said cam ring surrounding the slips and having a plurality of circumferentially spaced and inclined cam faces one for each of said slips and in supporting engagement therewith, and the cam ring being rotatable to move the slips vertically.

6. An elevator of the character described, comprising two body parts which together encircle the pipe, said body parts having a pipe receiving opening therebetween, means hinging the parts together at one end to enable one of the parts to swing horizontally to open and closed position, a pair of vertically movable wedge slips in said opening, one for each of said body parts, a segmental

slip actuating cam ring mounted within said opening and supporting said slips, the cam ring comprising two parts, one for each body part, and the ring being rotatable to move the slips vertically.

5 7. An elevator of the character described, comprising two body parts which together encircle the pipe, said body parts having a pipe receiving opening therebetween, means hinging the parts together at one end to enable one of the parts to swing horizontally to open and closed position, a pair of vertically movable wedge slips in said opening, one for each of said body parts, each of said slips having an integral projecting portion at its outer face, a segmental slip actuating cam ring mounted within an annular recess in the sides of the opening, the cam ring comprising two parts, one for each body part, and having a pair of inclined cam faces, one for each slip, and the projecting portions of the slips resting on said cam face, the cam ring being rotatable to move the slips vertically.

25 8. An elevator of the character described, comprising two body parts which together encircle the pipe having a pipe receiving opening therebetween, means hinging the parts together at one end to enable one of the parts to swing horizontally to open and closed position, a pair of vertically movable wedge slips in said opening, one for each of said body parts, each of said slips having a longitudinal rib on its outer face and extending within a channel in the side of said body opening, a longitudinally extending opening in each of said ribs and a roller mounted therein, a segmental slip actuating cam ring carried in an annular recess in the sides of said body opening and extending laterally through the openings in said slips, the cam ring comprising two parts, one for each body part, and having a pair of inclined slots, one for each wedge slip, said rollers riding the cam ring in said slots and the ring being rotatable to move the slips vertically.

45 9. An elevator of the character described, comprising pipe encircling body and gate portions having a pipe receiving opening therebetween, means hinging said portions together at one end to enable the gate to swing horizontally to open and closed positions, and a yoke extending around the hinged end of said body and gate portions.

55 10. An elevator of the character described, comprising pipe encircling body and gate portions having a pipe receiving opening therebetween, means hinging said portions together at one end to enable the gate to swing horizontally to open and closed positions, a yoke extending around both ends of the body and gate portions, one of the yokes being pivoted on the body and forming a latch for holding the gate in closed position.

11. An elevator of the character described, comprising pipe encircling body and gate portions having a pipe receiving opening therebetween, means hinging said portions together at one end to enable the gate to swing horizontally to open and closed positions, a plurality of vertically movable wedge slips within said opening, a yoke extending around both ends of the body and gate portions, one of the yokes being pivoted on the body and forming a latch for holding the gate in closed position.

70 12. An elevator of the character described, comprising pipe encircling body and gate portions having a pipe receiving opening therebetween, means hinging said portions together at one end to enable the gate to swing horizontally to open and closed positions, pipe gripping wedge slips within said opening and movable vertically within said opening to work engaging and releasing positions, and means for locking said body and gate portions in closed position, said locking means being releasable only when said pipe gripping means is in work releasing position.

75 13. An elevator of the character described, comprising pipe encircling body and gate portions having a pipe receiving opening therebetween, means hinging said portions together at one end to enable the gate to swing horizontally to open and closed positions, pipe gripping means within said opening and movable to work engaging and releasing positions, latch means for locking said body and gate portions in closed position, and means for locking said latch means to prevent opening of the gate when said pipe gripping means is in work engaging position.

80 14. An elevator of the character described, comprising pipe encircling body and gate portions having a pipe receiving opening therebetween, means hinging said portions together at one end to enable the gate to swing horizontally to open and closed positions, a pair of vertically movable wedge slips within said opening and mounted separately on said body and gate portions, means for locking said portions in closed position, and means for preventing said locking means from becoming released when the wedge slips are in lowered position.

85 15. An elevator of the character described, comprising pipe encircling body and gate portions having a pipe receiving opening therebetween, means hinging said portions together at one end to enable the gate to swing horizontally to open and closed positions, a yoke pivotally mounted on said body portion and adapted to extend around the free end of said gate to hold the gate in closed position and yielding means urging said yoke toward the gate, said gate having a cam face on its free end adapted to engage and swing said yoke as the gate is moved toward closed position.

16. An elevator of the character described, comprising pipe encircling body and gate portions having a pipe receiving opening therebetween, means hinging said portions together at one end to enable the gate to swing horizontally to open and closed positions, pipe gripping means within said opening and movable independently of the movement of said body and gate portions to work engaging and releasing positions, a yoke pivotally mounted on said body portion and adapted to extend around the free end of said gate to hold the gate in closed position, and yielding means urging said yoke toward the gate, said gate having a cam face on its free end adapted to engage and swing said yoke as the gate is moved toward closing position.

17. An elevator of the character described, comprising pipe encircling body and gate portions having a pipe receiving opening therebetween, means hinging said portions together at one end to enable the gate to swing horizontally to open and closed positions, pipe gripping means within said opening and movable independently of the movement of said body and gate portions to work engaging and releasing positions, a yoke pivotally mounted on said body portion and adapted to extend around the free end of said gate to hold the gate in closed position, yielding means urging said yoke toward its gate retaining position, and manually actuated means for swinging the yoke to gate releasing position.

18. An elevator of the character described, comprising pipe encircling body and gate portions having a pipe receiving opening therebetween, means hinging said portions together at one end to enable the gate to swing horizontally to open and closed positions, a plurality of vertically movable wedge slips within said opening, a segmental slip actuating cam ring within the opening and supporting said slips, the cam ring comprising two parts, one each for said body and gate portions, and being horizontally rotatable to move the slips vertically, a handle joined to said cam ring and extending outward through an enlarged opening in the gate, said cam ring being rotatable by operating the handle, latch means for holding and locking said gate in closed position, and means actuated by said handle for locking said latch means at one position of the cam ring.

19. In pipe supporting apparatus, a body having a tapered pipe receiving bore, a longitudinally movable wedge slip in said bore and having an outer cylindrical face engaging the bore wall, and the bore wall being recessed to form a cylindric way shaped in accordance with the outer face of the slip.

20. In pipe supporting apparatus, a body having a vertical and downwardly tapered pipe receiving bore, a vertically movable

wedge slip in said bore and having an outer cylindrical face engaging the bore wall the curvature of said face substantially corresponding to that of the lower end of said bore, and the bore wall being recessed to form vertically extending cylindric ways shaped in accordance with the outer face of the slips.

In witness that I claim the foregoing I have hereunto subscribed my name this 25th day of June, 1929.
